UNITED STATES PATENT OFFICE.

HENRY B. QUAIN, OF SAN JOSE, CALIFORNIA.

DESIGN FOR A HOLDER FOR A FOUNTAIN PEN OR THE LIKE.

Application filed November 23, 1927. Serial No. 24,262. Term of patent 14 years.

To all whom it may concern:

Be it known that I, HENRY B. QUAIN, a citizen of the United States, residing at San Jose, in the county of Santa Clara and State of California, have invented a new, original, and ornamental Design for a Holder for Fountain Pens or the like, of which the following is a specification, reference being had to the accompanying drawing, forming part thereof.

The figure represents a perspective view of the holder showing my new design.

I claim:

The ornamental design for a holder for a fountain pen or the like, as shown.

HENRY B. QUAIN.
